UNITED STATES PATENT OFFICE.

LIPA POLINKOWSKY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,387,171.

Specification of Letters Patent.

Patented Aug. 9, 1921.

Application filed February 20, 1919. Serial No. 278,178.

To all whom it may concern:

Be it known that I, LIPA POLINKOWSKY, a citizen of Russia, residing at New York, in the county of New York and State of New York, have invented certain new and useful Improvements in Telephone-Exchange Systems, of which the following is a full, clear, concise, and exact description.

This invention relates to telephone systems in which connections between subscribers' lines are extended in part by means of automatic switching apparatus and in part by the use of operators' link circuits.

More particularly, it has to do with a telephone system of this character wherein subscribers' lines are arranged to be extended by automatic switches over connecting circuits leading to operators' positions in a manual exchange, where the calls appear in answering jacks before the operator.

The object of the invention is to arrange for message registration by providing the subscribers' lines, as for example the subscribers' lines of an automatic satellite, with message registers located at the satellite, the operation of which is controlled by the operator in the exchange such that successful calls are charged to the calling line, whereas calls which do not succeed are not registered.

A feature of the invention consists in providing means associated with the finder switches in the satellite, and controlled by the operator at the exchange in such a manner that during the release of the satellite apparatus, at the end of a call, the register of the calling line is operated or not, depending upon whether or not the operator manipulated her charging device to register the call.

A further feature consists in the arrangement of a metering circuit containing a relatively high potential source, together with means under the control of the operator as soon as a connection has been established for preparing the metering circuit, so that during release of the satellite apparatus, such circuit will be completed and the high potential source applied to the calling line to actuate the message register thereon.

Such other features as are contemplated by the present invention will readily become apparent from a consideration of the following description.

In the drawings, which disclose a tele-

phone system embodying the features of this invention, Figure 1 shows a subscriber's line terminating in the satellite in the multiple contacts of first line finder switches. Fig. 2 shows one of a plurality of second line finder switches in the satellite arranged to extend connections over trunk circuits leading from the satellite to a manual exchange, where they appear in the answering jacks at an operator's position together with the answering end of an operator's card circuit. This figure also shows means associated with the connecting circuit of the second line finder controlled by a manually operated device at the operator's position for effecting the operation of message registers associated with the calling lines, and further, a subscriber's line local to the exchange appearing in a jack before the operator.

It is believed that a clearer understanding may be had of the invention from a description of the operation of the system in which the same is embodied.

It will be assumed that a subscriber in the satellite, such as the subscriber at substation 274, desires to obtain a telephone connection with a subscriber's line in the manual exchange. By removing his receiver from the hook, a circuit is established from battery 80 through the left-hand winding of line relay 201, contact and outer armature of cutoff relay 207 over the lower side of the line through the loop of a substation 274, back over the upper side of the line, inner armature and contact of cutoff relay 207 through the right-hand winding of relay 201 to ground. Relay 201 energizes and completes a circuit from battery, through the left-hand winding of common starting relay 204, re-

sistance 202, contact and armature of relay 201, resistance 203, to ground through the right-hand winding of relay 204. Through the left-hand winding of relay 204 and resistance 202, a selectable potential is also placed upon the multiple terminals 210 of all first line finders having access to the group containing the calling line. The starting relay 204 by attracting its armature closes a circuit for the power magnet 211 of all idle 100 first line finders, traceable from battery, armature and contact of relay 213, armature and back contact of test relay 212, through the winding of power magnet 211, winding of relay 205 to ground at the armature of 110

relay 204. The power magnets of such line finders operate to cause the movement of the brushes over the terminals of the group in search of the calling line. If the brush 275 5 of any idle line finder happens to be standing upon terminal 210 at this time, or as soon as the brush 275 of a searching finder reaches said terminal, a circuit is established from battery, through the left-hand winding of 10 relay 204, resistance 202, contact and armature of relay 201, terminal 210, brush 275 through the right-hand high resistance winding of test relay 214 to ground. Relay 214 thereupon energizes and closes a circuit 15 through its left-hand low-resistance winding, contact and armature, through the winding of the second test relay 212 to ground in parallel to its high resistance winding. The low resistance of this circuit causes a reduction 20 in the potential upon terminal 210 which will, in a known manner, render the calling line busy to other line finders. Relay 212 opens the above-traced power circuit and closes a circuit from battery through the armature and contact of relay 213, armature 25 and front contact of relay 212, through the holding magnet 215, through the winding of the common starting relay 216 to ground. Magnet 215 operates to bring the brushes of 30 the finder switch to rest accurately centered upon the terminals of the calling line, and the relay 216 closes a circuit to start the operation of idle second line finders. This circuit leads from ground through the armature 35 and contact of relay 216, sequence switch contact 226 of the sequence switch 220, armature and back contact of relay 232, sequence switch contact 223 bottom, through the winding of power magnet 241 to battery and ground. Magnet 241 causes the rotation of 40 the brush carriage to search for the terminals of the calling first line finder. The test relay 212 on operating, closes a circuit from battery, armature and contact of relay 213, armature and front contact of relay 212, 45 resistance 217 to the multiple terminals 230 of the second line finder switches, thereby placing a selectable potential thereon. As soon as the brush of a second line finder 50 reaches the terminal 230, a circuit is completed from such terminal through the right-hand high-resistance winding of test relay 234, sequence switch contact 227 top, to ground. Relay 234 by energizing closes a 55 circuit through its left-hand low resistance winding, contact and armature, sequence switch contact 229 top, through the winding of the second test relay 232 to ground, in parallel to its high resistance winding. The low 60 resistance of this circuit reduces the potential on terminal 230 to render the same nonselectable. As soon as the brushes are accurately centered, relay 232 energizes, opens the above-traced circuit for the power magnet 241 and closes a circuit from battery through 65

the winding of sequence switch magnet 220, contact 231 bottom, front contact and armature of relay 232, contact 226 top, to ground at the armature of the starting relay 216, driving the sequence switch 220 out of position 1. A circuit is also closed at this time from battery through the winding of the holding magnet 245, contact 222 top, contact 231 bottom, front contact and armature of relay 232, contact 226 top, to ground at the 70 armature of relay 216, which operates to properly position the brush carriage.

The number of second line finders in a group may be comparatively large, and in order to reduce the number of simultaneously 75 rotating second line finders during the slack hours, these finders are arranged in pairs so automatically controlled that only one line finder of each pair is able to search for a call at the same time. The manner in which this 80 is accomplished will appear presently.

As sequence switch 220 leaves position 1, the circuit through the high resistance winding of test relay 234 is opened at contact 227 top. On leaving position 3, the circuit 90 through the low resistance winding of relay 234 and the winding of relay 232 is also opened at the sequence switch contact 229 top. Sequence switch 220 on reaching position 3 closes a circuit from battery through 95 the winding of cutoff relay 207, terminal 218, relay 213, terminal 238, contact and left-hand armature of relay 224 to ground, over the sequence switch contact 233 bottom. Relay 213 by operating removes the potential 100 from the terminal 230 so that this circuit cannot be seized. This relay also opens the energizing circuit for the common starting relay 216, which thereby opens the power circuit of other searching second line finders. The cutoff relay 207 energizing in series 105 with the relay 213, disconnects the line relay 201 from the calling line, which in turn allows the starting relay 204 to be deenergized, thus opening the power circuit 110 for all first line finders which were started in operation by the initiation of the call. Test relays 214 and 212 also deenergize at this time.

It will be observed that the register magnet 208 associated with the calling line is connected in parallel with the cutoff relay 207 to ground when sequence switch 220 reached position 3. However, this magnet being marginal does not receive sufficient 115 current to operate.

As the sequence switch 220 moved into position 2, a circuit was completed to drive the sequence switch 220 of the other second line finder of the pair out of position 18, 120 where it stands while said finder is idle, into position 1, ready to control the finder on the incoming of another call. This circuit may be traced from ground, sequence switch contact 227 bottom, of the sequence switch 125 130

shown, conductor 276, conductor 277, over the sequence switch contact 222 at the other line finder, through the sequence switch magnet 220 to battery and ground. Upon 5 the sequence switch 220 of the line finder shown coming to rest in position 5, the test relay 232 is now energized in the circuit from battery, through the winding of relay 235, back contact and right-hand armature 10 of relay 224, sequence switch contact 229 bottom through the winding of relay 232 to ground. Relay 235 by attracting its armatures, closes the calling line in series with the supervisory relay 228 and the left-hand 15 winding of the repeating coil 237 including talking battery.

At the incoming end of the trunk line from the satellite there is provided in the manual exchange a line relay 251 and a cut-off relay 257. The incoming end of this 20 trunk appears in a jack 254 before the operator in exactly the same number as lines local to the manual exchange. The line relay 251 of the trunk line instead of being 25 connected to battery has its windings connected in series with each other across the conductors of the trunk.

When the sequence switch 220 in the satellite reached position 5, a circuit was closed 30 from battery through the winding of relay 239, sequence switch contact 240 bottom, over the upper conductor of trunk 250, right-hand armature and back contact of relay 253, outer armature and contact of cutoff relay 257, 35 through the windings of the line relay 251, contact and inner armature of relay 257, contact and left-hand armature of relay 253, over the lower conductor of the trunk 250, sequence switch contact 236 top, to ground 40 through the resistance 242. The line relay 251 energizes, but relay 239 being marginal does not receive sufficient current in series with the resistance 242 to attract its armature. Relay 251 causes the illumination of 45 the line lamp 252 in the usual manner. The operator observing this signal handles the call in exactly the same manner as calls appearing on lines local to the exchange. When the answering plug 261 is inserted 50 into the jack 254, a circuit is completed from ground through the winding of cutoff relay 257, sleeve of the jack and plug to battery and ground at the repeating coil 267 in the operator's cord circuit. Relay 257 55 opens the circuit of line relay 251 and a circuit is now completed for the windings of relay 239 over the upper conductor of the trunk 250, right-hand armature and back contact of relay 253, tip of jack 254, tip of 60 the plug 261 to ground at the repeating coil 267. Relay 239 energizes in this circuit and closes a circuit including the sequence switch contacts 244 and 243 bottom to drive sequence switch 220 out of position 5 and into position 12.

As soon as sequence switch 220 reaches position 6, the right-hand windings of the repeating coil 237 are connected to the trunk over contacts 240 and 236; the marginal relay 246 and release relay 225 being included in the 70 bridge across the trunk. The circuit of these relays may be traced from battery, in the operator's cord circuit, through the winding of supervisory relay 268, ring of the plug 261 and jack 254, back contact and left-hand 75 armature of relay 253, contact 236 bottom, lower right-hand winding of repeating coil 237, left-hand low resistance winding of relay 246, front contact and armature of calling line supervisory relay 228, left-hand 80 low resistance winding of relay 225, upper right-hand winding of repeating coil 237, sequence switch contact 240 top, right-hand armature and back contact of relay 253, tip 85 of the jack 254 and plug 261, to the other pole of battery. It will be noticed that the supervisory relay 228 being energized in series with the calling line, places a short circuit around the right-hand high resistance windings of relays 246 and 225. By this means 90 the resistance in the above-traced circuit is sufficiently low to permit the energization of relay 268 to short-circuit the calling supervisory lamp in the operator's cord circuit. Upon the calling subscriber replacing his receiver to the switchhook, relay 228 deenergizes and removes the short circuit around the high resistance winding of relays 246 and 225, causing the deenergization of relay 268 and consequently the display of the 95 supervisory signal. The relay 246 being marginal does not energize in the above-traced circuit. Relay 225, however, attracts its armature and closes a new circuit for relay 235 to ground in shunt of its original circuit, 100 which included the winding of relay 232. Relay 232 thereby releases its armature before sequence switch 220 can reach position 12, where it would otherwise continue to move by means of a circuit closed over contact 231 bottom, front contact and armature of relay 232 and contact 226 bottom. 105 The operator receives the number of the desired line from the calling subscriber and proceeds in the usual manner to complete the connection. If the called line is busy, if the called subscriber does not answer, or if for any other reason the call is not successfully completed, the operator does not depress her charge key 263 to register the call 110 against the calling line. On withdrawing the plug 261 from the jack of the trunk 250, release relay 225 is deenergized. On re-tracting its armature the above-described short circuit is removed from around the 115 winding of relay 232, which again energizes in series with relay 235. A release circuit is thereby closed for sequence switch 220 over contact 231 bottom, front contact and armature of relay 232, contact 226 bottom, to 120 125 130

ground. The sequence switch 220 moves out of position 12 through positions 13 and 14 and comes to rest in position 18, where it waits for the sequence switch 220 of the other line 5 finder of the pair to move out of position 1. In passing out of position 17, the circuit of relays 235 and 232 is opened at sequence switch contact 229 bottom, and these relays release their armatures. As the sequence 10 switch 220 leaves position 14, contact 233 bottom is also opened and relays 213 and 207 are deenergized. The cutoff relay 207 connects the line relay 201 to the subscriber's line ready for the initiation of another call. 15 If the operator establishes a successful connection to the called line, she is advised of this fact by the usual called line supervisory signal. She thereupon depresses the charge key 263 to prepare for the operation of the 20 message register 208 individual to the calling line. The actuation of key 263 closes a circuit from battery, through the winding of magnet 264, key 263, sleeve of the plug and jack through the right-hand winding of relay 258, to ground. Relay 258, being marginal, did not operate in parallel with the cutoff relay 257, but does receive sufficient current in the circuit just traced to attract its armature. The energization of relay 258 25 closes a circuit through its left-hand low resistance winding, contact and armature, to ground through the winding of low resistance relay 253 in parallel to the circuit through the right-hand high resistance winding of relay 258. The resistance in 30 series with magnet 264, which is also marginal, is now reduced sufficiently to permit said magnet to energize and operate the register at the operator's position. Relay 253 attracts its armatures and places the high voltage battery 256 across the trunk line 35 250 through a retardation coil 255. The increased flow of potential from the battery 256 is now sufficient to cause the operation of marginal relay 246 in the satellite. Relay 246 closes a circuit from the metering battery 249 through the armature and contact of relay 246, resistance 247, through the winding of marginal relay 239, to the opposite pole of battery and ground. Relay 239 40 closes a locking circuit for itself independent of the armature and contact of relay 246, from battery through the winding of relay 239, resistance 247, sequence switch contact 45 243 top, contact and armature of relay 239, sequence switch contact 244 top to the metering battery 249 and ground. The retardation coil 255 serves to reduce the inductive effect to prevent annoying clicks in the subscriber's receiver in case the operator depresses the key 263 to charge the call during 50 the period that the subscribers are in conversation. As soon as the key 263 is released, relay 253 retracts its armatures and 55 completes trunk circuit 250 for conversation. 60 65

When marginal magnet 264 energized, it closed a circuit for lamp 280 to inform the operator that the mechanism for bringing about the registration of the call had operated and that charge key 263 might be released. 70

After the conversation has been completed, the operator withdraws the plug 261, release relay 225 deenergizes, relay 232 attracts its armature and sequence switch 220 75 starts from position 12 and moves into position 18 in the manner hereinbefore described. In this instance, however, since the operator has impressed her charge key 263, a metering circuit has been prepared for 80 the operation of register 208, which circuit is now completed by the sequence switch 220 as it is moving through its releasing positions. This circuit may be followed from the positive pole of the metering battery 85 249, sequence switch contact 244, armature and contact of relay 239, sequence switch contact 243 top, sequence switch contact 233 top, left-hand armature and contact of relay 224, winding of relay 213, through the 90 winding of the marginal magnet 208, to the negative pole of battery and ground. This circuit it will be seen is closed while the sequence switch 220 is passing from position 95 14 to position 18, and the increased flow of current is sufficient to operate the message register magnet 208 to charge the call.

Should the calling subscriber abandon the call after his line has been extended over a trunk to the manual exchange before the 100 operator answers by inserting a plug in the jack of the trunk, the supervisory relay 228 becomes deenergized. As has been seen, the sequence switch 220 is standing in position 5 at this time. A circuit is therefore closed 105 from ground, through sequence switch contact 248 top, armature and back contact of relay 228, sequence switch contact 231 top, to drive the sequence switch 220 into position 12. In position 12, since relay 225 is deenergized, the operator having failed to answer the call, no shunt exists around relay 232, and hence relays 235 and 232 are energized in series. The above-traced release circuit for sequence switch 220 is therefore 110 closed at the front contact of relay 232, and said sequence switch is driven into its eighteenth position. 115

Relay 224 serves to secure a proper premature release of the trunk line in case two 120 second line finders happen to stay on the terminal of a calling first line finder, and the high resistance windings of the test relays 234 may both become energized and connect in the circuit their respective relays 232, 125 which when energized may cause the starting of their respective sequence switches 220 from their position of rest. When the sequence switch 220 leaves position 1, the high resistance winding of relay 234 is discon- 130

nected and the low resistance winding of this relay is not able to maintain its energization if two test relays are brought in parallel with the same terminal 230. Relay 5 234 thereby releases its armature and in consequence relay 232 is deenergized. On passing to position 2, sequence switch 220 closes a circuit from battery through the winding of relay 224, contact 223 top, back contact 10 and armature of relay 232, to ground at contact 226 bottom. Relay 224 energizes and is maintained energized in position 3 of the sequence switch over its front contact and armature to ground at sequence switch contact 15 248 bottom, and remains energized in positions 4 to 17 in series with relay 232, which circuit may be traced from battery, through winding of relay 224, front contact and right-hand armature thereof, sequence 20 switch contact 229 bottom, winding of relay 232 to ground. Relay 232 energizes and closes the above-traced release circuit for the sequence switch 220, which moves into position 18. Relay 224 by energizing prevents 25 the operation of relay 235 from connecting the repeating coil 237 to the calling line.

As hereinbefore explained, the trunk circuits 250 coming from satellites or other automatic switching points may appear indiscriminately before the operator among the local lines to the exchange. By the arrangement used, call registration for the satellite lines, together with call registration for lines 30 local to the exchange, is controlled at the operator's position, circuit by the same means, without it being necessary for the operator to know what kind of a call she is handling.

In Fig. 2 is shown a local subscriber's line 40 284 terminating in jack 281 at the operator's position. The line relay 282 in this case is operated in the usual manner by battery at the exchange. With plug 261 inserted in jack 281, the operator by closing her 45 charge key closes a circuit over the sleeve of the plug 261 and jack 281 to energize the marginal magnet 283. This circuit includes marginal magnet 264 and is similar to the circuit traced for marginal relay 258 in connection with a call over trunk 250. Magnet 283 operates to register the call against the local calling line and to close a circuit through its low resistance winding to permit the energization of magnet 50 264, which causes lamp 280 to light, thus informing the operator that registration is properly taken care of and the key 263 may be released.

A feature to be observed in the metering 60 arrangement embodying this invention is that the operator in the manual exchange may prepare for the registration of a call in the satellite at any time after she has learned that the call was successfully extended. By this means she may depress her

charge key immediately upon the operation of the called supervisory signal, if desirable, and go on with her duties without having to carry in mind that the call must be charged at the time of disconnection. 70

What is claimed is:

1. In a telephone system, telephone lines, an operator's position, connecting circuits for extending said lines to the operator's position, a register associated with each of 75 said lines, automatic means for operating said registers during the release of the connecting circuits, and means under the control of the operator for rendering effective said automatic means. 80

2. In a telephone system, telephone lines, an operator's position, automatic switches for extending a calling line to said position, a message register associated with said line, means operative during the release of said 85 switches for operating said register, and means under the control of the operator for rendering said means effective.

3. In a telephone system, telephone lines, an operator's position, automatic switches 90 for extending a calling line to said position, a message register associated with said calling line, a controlling sequence switch individual to one of said switches, means operative under the control of said sequence 95 switch for operating said register, and means controlled by the operator for rendering said sequence switch effective to control said means.

4. In a telephone system, telephone lines, 100 automatic switches for extending said lines, a register associated with each of said lines, register controlling means automatically operative upon the release of said switches to operate said registers, and manual means 105 for rendering said controlling means effective to operate said registers.

5. In a telephone system, telephone lines, an operator's position, means comprising 110 automatic switches for extending said lines to establish connections, registers, one associated with each of said lines, means automatically operated upon the release of a connection for controlling the operation of said registers, and means under the control 115 of the operator as soon as a connection has been extended for placing said registers under the control of said automatically operated means.

6. In a telephone system, telephone lines, 120 a line finder for extending said lines, a controlling switch for controlling said finder, a message register associated with each of said lines, means under the control of said controlling switch for operating said register during the release of the line finder, and manual means for rendering such controlling switch effective to control the operation 125 of said register.

7. In a telephone system, telephone lines, 130

a connecting circuit for extending said lines, a device for controlling said connecting circuit, message registers associated with said lines, a source of current for operating the 5 message registers, said controlling device being operative to apply said source to the message registers during the release of said connecting circuit, and manually operated means for rendering said source subject to 10 the control of the controlling device.

8. In a telephone system, telephone lines, a connecting circuit for extending a calling line, a message register associated with the calling line, an operating circuit for 15 said register normally open at two points, automatic means for closing said operating circuit at one point each time said connecting circuit is released, and manually controlled means for closing the operating circuit at the other of said points. 20

9. In a telephone system, a satellite, subscribers' lines terminating therein, an exchange, an operator's position in the exchange, trunks inter-connecting the satellite and exchange, automatic switches for extending a calling line to one of said trunks, a message register associated with the calling line, automatic means in said satellite for controlling the operation of 25 said register during the release of the automatic switches, and means under the control of the operator for rendering said automatic means effective to cause the operation of said register. 30

35 10. In a telephone system, a satellite, subscribers' lines terminating therein, an exchange, trunk lines interconnecting said satellite and exchange, an operator's position in said exchange, automatic switches for extending a connection from a calling 40 line in the satellite over one of said trunks to the operator's position, a message register associated with the calling line, means in the satellite for automatically controlling

the operation of the message register during the release of said connection, and means subject to the control of the operator as soon as said connection has been extended for rendering said first means effective to control the message register. 45 50

11. In a telephone system, an operator's position, a line terminating in said position, a second line, automatic switches for extending the same to the operator's position, a register associated with each of said lines, a manually operable device at said operator's position for causing the operation of the register associated with said first line, means automatically operated upon the release of said switches for controlling the operation of the register associated with said second line, and means responsive to the operation of said manually operable device for placing the last-mentioned register under the control of said automatically operated means. 55 60

12. In a telephone system, an operator's position, a line terminating in said position, a second line, automatic switches for extending the same to the operator's position, a register associated with each of said lines, a manually operable device at said operator's position for causing the operation of the register associated with said first line, means automatically operated 70 75 upon the release of said switches for controlling the operation of the register associated with said second line, means responsive to the operation of said manually operable device for placing the last-mentioned register under the control of said automatically operated means, and a signal at the operator's position operated each time said manually operable device is operated. 80

In witness whereof, I hereunto subscribe 85 my name this 11th day of February, A. D. 1919.

LIPA POLINKOWSKY.
